CLAIM

The ornamental design for a threaded connector, as shown and described.

DESCRIPTION

FIG. 1 is a perspective view of a threaded connector;

FIG. 2 is a top plan view of the threaded connector;

FIG. 3 is a bottom plan view of the threaded connector;

FIG. 4 a front elevation view of the threaded connector, the rear elevation view is a mirror image thereof; and,

FIG. 5 is a right side elevation view of the threaded connector, the left side elevation view is a mirror image thereof.

The threaded connector is shown with a symbolic break in its length. The broken lines and the appearance of any portion of the article between the break lines forms no part of the claimed design.
